(57) **CLAIM**

The ornamental design for a rugged, water and dust resistant handheld and mountable GPS device, as shown and described.

DESCRIPTION

FIG. 1. is a frontal perspective view of a rugged, water and dust resistant handheld and mountable GPS device according to the present invention;

FIG. 2. is a front elevational view thereof;

FIG. 3. is a top plan view thereof;

FIG. 4. is a left end view thereof;

FIG. 5. is a right end view thereof;

FIG. 6. is a bottom plan view thereof;

FIG. 7. is a rear elevational view thereof;

FIG. 8. is a rear perspective view of the rear antenna assembly fully raised thereof; and,

FIG. 9. is a rear perspective view of the rear antenna assembly fully raised and turned thereof.
